UNITED STATES PATENT OFFICE.

WILLIAM N. PICKETT, OF RICHMOND, CALIFORNIA.

TARGET-CARRIER.

1,160,753.

Specification of Letters Patent. Patented Nov. 16, 1915.

Application filed September 18, 1914. Serial No. 862,318.

To all whom it may concern:

Be it known that I, WILLIAM N. PICKETT, a citizen of the United States, and a resident of Richmond, in the county of Contra Costa and State of California, have invented certain new and useful Improvements in Target-Carriers, of which the following is a specification.

My invention relates to shooting ranges or galleries, and the main object thereof is to provide means for exposing a target in position for practice, delivering the same to the marksmen, and returning a fresh target to practice position, without requiring the operator to expose himself to the common danger of being shot, or of the loss of time now necessary to carry a target from the practice position to the marksman, and to substitute a fresh target for the one removed.

My invention is fully described in the following specification, of which the accompanying drawings form a part, in which the separate parts are designated by the same reference characters in each of the views, and in which:

Figure 1 is a view of the apparatus in the position of a marksman, or range operator; Fig. 2 is a view of the apparatus at the normal target position, with the target carrier held thereat; Fig. 3 is an enlarged, partial, section taken on the line 3—3 of Fig. 2; and Fig. 4 is a section taken on the line 4—4 of Fig. 3.

In the drawings forming a part of this application I have shown a present preferred form of embodiment of my invention, comprising a carrier 5 movable along a wire 6, an engaging hook 7 on a plate 8 in the normal target position and provided with a cord 9, and the apparatus in the position of the marksman.

The carrier 5 comprises a cylinder 11 closed at each end but having a rod 12 projecting from the end thereof farthest from the marksman, which rod is normally held in outermost position by means of a spring 13, and the cylinder 11 is supported upon the wire 6 by means of pulleys 14, and provided with a lug 15 adapted for engagement with the hook 7, which is normally forced upwardly by means of a spring 16 and constitutes a latch for normally holding the

cylinder 11 in its position farthest removed from the marksman.

The rearward end of the cylinder 11 carries an arm 17 provided with a rack 18 arranged above the wire 6, and with an arm 19 thereunder carrying a cylinder 20 within which is a rod 21 carrying a dependent lip 22 at its forward end and normally held in rearward position, as shown in Fig. 2, by means of a spring 23, the lip 22 acting, with a fixed lip 24 on the cylinder 20, as a clutch for a card 25 which constitutes the target, but it will be seen that, if the rod 21 is forced forwardly, the target card is released and will fall from the carrier.

The apparatus in the position of the marksman comprises a support 26 having a gear-wheel 27 rotatable thereon and in such position as to be engaged by the rack 18 in the rearward movement of the carrier 5, as clearly shown in Fig. 1, and said gear is joined to a sprocket-wheel, not shown in detail, by means of a suitable clutch, indicated in dotted lines in Fig. 1, permitting free revolution of the gear 27 in a direction opposite the arrow but carrying said sprocket-wheel with it when revolved in the direction of the arrow, and which sprocket-wheel 80 is connected with a sprocket-wheel 28 on a shaft 29 arranged in a box 30 secured to said support 26, and which shaft carries wheels 31 within said box.

Horizontally slidable in channels 32 in the sides of the box 30 is a target magazine 33, which is also supported by means of anti-friction rollers 34 moving upon the bottom of the box, and said magazine is normally forced forwardly by means of one or more weights 35 carried by cords 36 guided over a pulley 37 and secured to the back 38 of the magazine 33, a plurality of targets being shown in said magazine.

The top of the box 30 is slotted in the position of the outermost target in the magazine, and said slot is protected by spring clips 39 to prevent the upward passage of more than one fresh target at a time, the wheels 31, in their rotation by means of the sprocket-chain 40, serving to move the targets upwardly, successively, being provided with pin points or the equivalent upon its periphery, for this purpose, and I provide

a supplemental, idle, roller 41 to limit the forward movement of the fresh targets in the magazine.

Also supported upon the support 26 is a cylinder 42 arranged in the axial line of the carrier cylinder 11, and within which is a plunger 43 normally forced forwardly by means of a spring 44, being retracted by means of a cord or cable 45 passed over suitable pulleys 46 and 47 and thence to a pedal 48 upon the floor or ground, or in any other suitable place, and said plunger is held in retracted position by means of a latch 49 extending forwardly of the cylinder 42 and engaging a lug 50 on the plunger, said latch being pivoted at 51 and being normally held in plunger locking position by means of a spring 52.

The target carrier is normally in the position shown in Fig. 2, engaged with the latch 7, and with the rod 12 therein retracted against the spring 13, this occurring when the carrier had been forced into this position through the forward end of the rod 12 striking against the plate 8, and the cord 9 of this latch is led to a suitable pedal 53, by means of which the carrier may be released.

When the pedal 53 is moved, the latch 7 is drawn downwardly, and the spring 13 forces the carrier rearwardly until the cylinder 11 strikes against the extended end of the latch 49; before this occurs, the rack 18 engages and revolves the gear 27 and the roller 31 within the box 30 is rotated, thereby moving a new target card upwardly; as this is being done, the rod 21 strikes against a fixed lug 54 on the cylinder 42, and is forced forwardly against its spring, thus releasing the used target card, which falls to the counter of the shooting gallery, for the inspection of the marksman who had shot thereat, and the clutch formed by the lips 22 and 24 is now open and ready to receive a fresh target which has been moved between said lips; this engagement of the cylinder 11 with the latch 49 releases the latter, and the plunger 43 is forced forwardly by its spring at high speed, and thus imparts sufficient impetus to the carrier to drive it to its normal position, to retract its rod 12, and to pass within the latch 7, and the fresh target is ready for another trial of marksmanship.

As soon as the new target has been started on its way, the operator, by means of the pedal 48, again retracts the plunger 43 and the device is ready for another operation, and it will be understood that I may employ a number of pedals for each of the two purposes in different positions along the counter of the gallery, or I may substitute levers therefor adapted to be actuated by hand, or I may dispense with them entirely and depend upon the cords or cables alone;

I may also, if desired, actuate the same by suitable power controlled from any desired place or places, these features being optional with myself.

It will thus be seen that I provide a carrier for a target which brings the used target to the marksman, and engages a new target for carriage to the normal target position, and I also provide suitable actuating mechanism for the carrier in the two directions, thus eliminating any possibility of the operator being shot, as he is not compelled to walk the length of the range to secure the used target.

I may make desired structural changes, within the scope of the following claims, without departing from the spirit of my invention, or sacrificing its advantages.

Having fully described my invention, what I claim as new, and desire to secure by Letters Patent, is:—

1. The combination of a guiding wire, a carrier thereon, means for normally holding the same at one end of said wire, releasing means therefor, means for driving the same to the other end of said wire, automatic means for releasing the target carried, automatic means for feeding a new target thereto, and means for driving said carrier to initial position.

2. The combination of a guiding wire, of a carrier thereon, a latch for normally holding the same at one end of said wire, means for actuating said latch to release said carrier, means for driving said carrier to the other end of said wire, automatic means for releasing the target carried, automatic means for feeding a new target thereto, and means for driving said carrier to initial position.

3. The combination of a guiding wire, a carrier thereon, means for normally holding the same at one end of said wire, releasing means therefor, a normally retracted, spring-actuated rod for driving said carrier to the other end of said wire, automatic means for releasing the target carried, automatic means for feeding a new target thereto, and means for returning said carrier to initial position.

4. The combination of a guiding wire, a carrier thereon, means for normally holding the same at one end of said wire, releasing means therefor, means for driving said carrier to the other end of said wire, a target clutch carried by said carrier, automatic means for opening the same to release the target carried, automatic means for feeding a fresh target to said clutch, and means for returning said carrier to normal position.

5. The combination of a guiding wire, a carrier thereon, means for holding the same at one end of said wire, releasing means therefor, means for driving said carrier to the other end of said wire, means for re-

leasing the target carried, means for feeding a new target thereto, a spring actuated plunger normally under tension, a latch therefor, and means connected with said carrier for actuating said latch to release said plunger to return said carrier to normal position.

In testimony whereof I have signed my name to this specification in the presence of two subscribing witnesses.

WILLIAM N. PICKETT.
